CLAIM

The ornamental design for an automatic water dispenser for pet, as shown and described.

DESCRIPTION

FIG. 1 is a front elevation view of an automatic water dispenser for pet showing my new design;

FIG. 2 is a rear elevation view thereof;

FIG. 3 is a left elevation view thereof;

FIG. 4 is a right elevation view thereof;

FIG. 5 is a top elevation view thereof;

FIG. 6 is a bottom elevation view thereof;

FIG. 7 is a perspective view thereof; and,

FIG. 8 is a another perspective view thereof.
